UNITED STATES PATENT OFFICE.

HUGO ALTSCHUL, OF CHICAGO, ILLINOIS.

COIN-PACKAGING MACHINE.

984,522.

Specification of Letters Patent. Patented Feb. 21, 1911.

Application filed December 2, 1907, Serial No. 404,840. Renewed November 25, 1910. Serial No. 594,212.

To all whom it may concern:

Be it known that I, HUGO ALTSCHUL, a subject of Austria-Hungary, residing at the city of Chicago, in the county of Cook and State of Illinois, have invented certain new and useful Improvements in Coin-Packaging Machines, of which the following is a specification.

This invention relates to improvements in coin packaging machines and has among its salient objects to provide a construction which automatically collects the coins in rolls, wraps and seals each roll, stamps the same and finally delivers it ready for use; to provide a simple and compact device in which the packaging mechanisms are all operated by a single crank; to provide a construction which can be adjusted to the packaging of coins of various denominations; to provide improved means for gumming, cutting and delivering the wrappers to the carriages in which the rolls of coin are held while being packaged; to provide a series of traveling carriages whereby the process of packaging coins may be performed continuously; to provide improved means for automatically compressing each roll of coins into a compact roll at the time that they are being wrapped; to provide improved means for feeding the coins into the delivery chute and for automatically delivering each roll separately at the proper time; to provide improved means for gumming and sealing each end of the roll of coins after it has been wrapped; and in general to provide an improved construction of the character referred to.

Referring to the drawings Figure 1 designates a longitudinal sectional view of my improved coin packaging machine, the upper part of the hopper and chute however being broken away to reduce the size of the drawing. Fig. 2 is a side elevation of the hopper and part of the delivery chute, part of the casing of the hopper however, being broken away to show details of construction. Fig. 3 is a plan view of the machine, parts being broken away to expose subjacent parts. Fig. 4 is a front end elevation of main parts of the device, the hopper being shown in transverse vertical section. Fig. 5 is a transverse sectional view, on a large scale, the left hand side of the figure being taken approximately through line 5—5 of Fig. 1 while the right hand side is taken through line 5'—5' of the same figure; the figure be-

ing taken on different sectional lines in order to more clearly show the manner of compressing the coins. Fig. 6 is a sectional view on a still larger scale showing details of construction of the carriage and delivery end of the chute. Fig. 7 is a sectional detail view showing the manner of sealing the ends of the compressed packages.

Referring to the drawings 1 designates as a whole a box like frame having at one end an inclined upwardly projecting extension 2. The forward end of the base of the frame is cut out at 3 to form a delivery chute for packaged coins. Transversely extending skeleton frame members 4 and 5, respectively, extend upwardly from the main frame. These skeleton frame members serve as supports for adjustably extending tracks 4' and 5', respectively. As will appear the endless conveyer is trained to ride over the respective tracks 4' and 5'. Adjustable cover members 6 and 7 inclose the top of the frame as well as serve other purposes hereinafter described. The cover 6 is curved downwardly and rearwardly at its forward end to inclose the front of the frame as shown clearly in Fig. 1.

The coins are delivered to the packaging device from a chute 8 which is in turn fed from a hopper 9. Describing this delivery mechanism, the chute 8 is secured to the inclined support 7' at the rear of the frame and is of slightly less width than the frame members, as shown clearly in Fig. 3. In order to permit of access to this chute in case any coin becomes lodged therein or for any other purpose, the former is provided with a glass top 10 which is hinged at 11—11 to the frame member as seen in Fig. 4. This chute is subdivided by a series of parallel steel plates 13 which extend longitudinally of the chute and are spaced apart so as to confine one row of coins piled edge upon edge between each pair of plates, while at the same time permitting the coins to fall freely down to the packaging device. As seen in Fig. 1 these plates are about half the height of the chute 8 and at their lower ends are bent outwardly in order to more accurately guide the coins into the carriages. At their upper ends the plates register between openings in the lower end of the hopper 9, whereby the coins fall from the hopper down between the pairs of plates 13. It is obvious that when the mass of coins is emptied into the hopper only a few of them will fall into the chute

through the relatively narrow openings between the plates, unless some means are provided for agitating or shaking the coins into proper position to pass between the plates.

5 To the above end, the hopper, which may be of any preferred general construction, is so mounted as to be bodily reciprocated across the upper end of the chute. Mechanism is also provided within the hopper itself for 10 agitating the coins. Describing this latter mechanism the hopper is loosely supported upon a rod or shaft 14 which is rotatably journaled between bracket arms 15 which extend upwardly from the top of the frame 15 member. Upon this rod 14 are fixedly secured two oppositely extending rows of agitator fingers 16 which as the rod is rotated agitate the mass of coins within the hopper. At one end the rod 14 is provided 20 with a bevel gear 17 which meshes with another gear 18 rigid with a driving shaft 19 mounted in the frame member. This shaft is manually operated by a simple crank arm 21 having a handle 22. In order that the 25 mechanism which operates the agitator fingers may at the same time bodily reciprocate the hopper, a relatively large pinion or gear 23 is keyed to the outer end of the shaft 19 and meshes with a smaller pinion 24 30 which is in turn keyed to a secondary shaft 25 rotatably journaled in the frame member. This shaft 25, as seen more clearly in Fig. 4, carries a pair of oppositely extending cam arms 26 which serve to reciprocate the hopper when the shaft is rotated. To this end, 35 the hopper is provided on its outer face adjacent to the cams with blocks 27 and beneath the blocks it is cut away to form openings 28. It will thus be seen that upon every 40 half revolution of the shaft 25, one of the cam arms will first impinge against its corresponding block 27 thus forcing the hopper toward the opposite side of the chute, and upon the further rotation of the shaft 25 45 wipe through the openings 28 thus permitting the hopper to return to normal position. In order to automatically return the hopper after it has been reciprocated by either of the cams it is provided with one or more 50 coiled springs 29 mounted on bolts 30. These bolts have their headed ends seated rigidly in the side of the hopper while the outer ends extend loosely through guide openings in the adjacent supporting brackets 15.

55 Mechanism is provided for confining the coins against escaping from the chute, also for delivering a row efficiently at the proper time. To the above end I provide a spring pressed gate 31 which extends transversely 60 across the lower end of the chute, and is parti-circular at its outer face in order to more accurately fit the edges of the lowermost row of coins. This gate is mounted to reciprocate in sockets 32' which are fixed 65 upon the brackets 32'' secured at either side

of the upstanding portion 2 of the main frame. The springs 31' tend to press the gate normally outwardly. To eject each row of coins singly from the chute, I provide a bail 33 which is mounted in the frame at 70 either side thereof and extends across and above the lowermost row of coins. This bail is normally held uplifted in the position shown in Fig. 1 by springs 33' and is adapted to be forced downwardly as hereinafter 75 described, thus ejecting the lowermost row of coins and forcing the gate 31 back against the action of its spring and permitting said row of coins to drop into a carriage. It is obvious that when the gate 31 is forced back- 80 wardly against its spring some means must be provided for confining the remaining coins within the chute. To this end the rod 33 is provided at its upper end with an up- 85 standing plate 33'' which extends transversely across the lower end of the chute when the bail 33 is forced downwardly as shown clearly Fig. 6.

Describing now the mechanism for packaging the coins, a pair of shafts 35—35 are 90 journaled at either end of the main frame and upon the respective ends of each of these shafts is keyed a sprocket wheel 34. These shafts are operatively connected with each other by means of a pair of endless chains 95 36 trained around the sprockets 34 as shown in Fig. 1. In order to operate the shafts and chains, a pulley 36' is keyed to the rear shaft 35 and around this pulley is trained an endless belt 37 which is also trained 100 around a smaller pulley 38 journaled in the rear of the frame and rotated by hand crank 39. For purposes hereinafter described the upper and lower laps of the pair of conveyor belts are confined against downward 105 movement by being arranged to ride on the tracks hereinbefore described. Between the chains 36 are rigidly mounted, by means of downwardly extending leg portions 41, a series of traveling carriages 40 which also 110 ride upon the tracks 4'. Each of these carriages comprises a transversely extending trough-shaped main body 42 and a supplemental spring back 43, the latter being mounted on spring pressed rods 44 which 115 extend loosely through the upturned edge of the main body. This spring back 43 is normally forced forwardly and co-operates with the front side of the main body to securely grip a row of coins. In order that 120 the paper in which the coins are wrapped may not catch in the operating mechanism, the rear end of each spring back is bent outwardly to form fenders 45. Upon the forward end of each carriage is fixed an inking pad 46 which in the travel of the carriage wipes across and so serves to ink a type plate 46' fixed in the front part of the frame. Beneath the carriage, a rod 50 is mounted in supports 51, 51' formed in the 125 130

carriage frame; and between the middle and each of the outer supports the carriage bottom is provided with a slot 52. Within each of these slots is mounted a U-shaped arm 5 compressor 47 which is normally forced outwardly by means of a coiled spring 47' upon the rod 50. The upper end of each arm 47 is provided with an inwardly extending enlarged head portion 48 adapted to 10 compress the row of coins, while the lower end of each arm carries a stud 49 which normally rides against the inner face of its respective track 4' through the action of the spring 47'. The arms 47 are forced inwardly 15 at the proper time to compress the coins, by means of cam extensions 53 which coöperate with studs 49 as will hereinafter appear. Upon the respective chains at points slightly in advance of each end of the carriages is 20 secured an upstanding lug 54 which is inclined at its outer end. These lugs are adapted to engage studs 55 upon the lower ends of the bail 33 and thus force the latter downwardly to eject a row of coins, as heretofore described. It is to be here noted that the carriages are so spaced apart that when any pair of lugs 54 wipe by the studs 55, the immediately preceding carriage will be in 25 position to receive a row of coins from the chute.

Describing now the mechanism for delivering the paper wrappers to each carriage, a shelf 56 extends across the rear end of the frame in the plane just below the lower end 35 of the chute. At either side of this shelf is mounted a spring pressed rod 57, and between these rods at the rear end thereof is secured a mucilage box 58 and a knife 59. The knife and box are adapted to be forced 40 downwardly against the paper as the latter passes over the shelf, and in order to more effectively cut the paper the knife is arranged to reciprocate through a slot 59' formed in the shelf. The forward ends of 45 these rods 57 pass through slots formed in the top member 7 and extend beneath studs 60 extending from the bail 33. At the rear of the rods, a drum 61 is rotatably journaled in arms 62 extending from the sides of the 50 shelf 56. This drum is rotated by frictional engagement with a roller beneath it, which in turn is actuated by the crank arm 39. The wrapping paper 63 is drawn from the roll 64 by frictional engagement between 55 the rolls 61 and 64', the latter being mounted on the crank 39. It will thus be seen that as the bail 33 is forced downwardly by the lugs 34 the studs 60 engage the forward ends of the rods 57 and force the mucilage box and 60 knife downwardly thus simultaneously gumming and cutting the paper. When the bail returns to its normal position the spring pressed rods 57 will of course return to normal position carrying the box and knife out 65 of contact with the paper. It will be noted

that the mechanism is so arranged that the free end of the paper will overlap the forward and oncoming carriage just before the paper is gummed and cut.

When the bail has been actuated the lowermost roll of coins will pass into the carriage, forcing back the spring member 43 which thereupon through the action of its springs holds the coins firmly with the carriage. As the roll of coins falls into the carriage the wrapper which at this time extends across the face of the carriage will be carried downwardly so that its forward end will be held frictionally between the roll of coins and the front wall of the carriage. Upon the inner face of the adjustable cover member 6 is fixed a rubber lining 65 which is adapted to have such frictional engagement with the upper edge of the roll of coins as to rotate the latter as the carriage advances. It will thus be seen that upon the advance of the carriage the roll of coins will automatically wrap itself as shown clearly in Fig. 1. In order that the front end of the wrapper may be bent rearwardly 80 and downwardly as the carriage advances, in order to completely keep the roll of coins, I provide a plurality of guide fingers 66 which are pivotally mounted upon a rod 67 which extends through a transverse opening in the top of the member 6. This opening is of sufficient width to permit the fingers 66 to reciprocate therethrough as shown clearly in Fig. 1. Upon the further rotation of the row of coins within the carriage 85 the gummed end of the wrapper will be folded across the row of coins and there sealed.

As the carriage traverses the tracks, the studs 49 of the spring arms 47 will encounter the cam members 53, forcing the arms 47 inwardly and thus compressing the rolls of coins as heretofore described. When the carriage rides by the cam extension, the arms 47 will of course spring back to their 105 normal position. The roll of coins has now been compressed and completely wrapped except for the sealing of the ends of the package. To accomplish this end, four laterally opposite pairs of brackets 68 are secured 110 at the sides of the front end of the frame member and extend upwardly above the top of the latter to form guide ways 69. Within each pair of aligned guide ways, is mounted a rod 70 which extends across the frame and 115 is normally held in the upper ends of its respective guide ways by springs 71. At each end each rod 70 is provided with a stud extension 72 which carries a hollow folding finger 73. These fingers, of which there are 120 four at each side of the frame are wedge shaped in cross-section at their lower ends and conform approximately in area to one fourth the area of the face of a coin. These fingers are flat at their inner faces and bevelled 125

eled at their outer portions. In order that the ends of the wrapper may be sealed when they are bent across the ends of the roll of coins, the first three pairs of fingers are filled with mucilage which escapes on to the paper through slots 73' cut in the lower inner face of the respective fingers.

Each pair of fingers is adapted to be successively forced downwardly across the ends 10 of the package. To this end each rod carries at either end a link 75' which is respectively connected with a bell crank 75 mounted on a journal or stud 76. Each bell crank is provided at its lower end with a wiper 15 77 which extends downwardly so as to engage a stud 78 upon the carriage, whereby the advance of the latter will operate the crank and force the rod 70 carrying the finger 73 downwardly, thus folding down 20 a portion of the wrapper. As the carriage continues to ride forwardly and the roll of coins to rotate, the carriage will in turn engage each pair of wipers 77 and thus operate each pair of fingers 73. It will thus 25 be seen that the ends of each package will be automatically closed and sealed.

The package is now ready to be printed for identification. As heretofore described each carriage carries an inking pad 46 which 30 co-operates with a type plate 46' to ink the latter. As the carriage advances, the package will continue to rotate through its frictional engagement with the rubber plate and will thus gradually roll on the printing form 46' and stamp the roll for identification. In order that the type within the 35 form 46' may be changed when desired, I provide a normally closed opening 46'' within the front of the frame through which the 40 form may be removed.

To more certainly seal the ends of the package of coins, I provide a pair of semi-circular guard arms 79 secured at either end of the frame and slightly approaching 45 each other toward their lower ends. The package is now automatically delivered from the carriage into the delivery chute 3 by the spring back 43 engaging an upstanding projection 80 on the lower part of the frame 50 member and thus being forced backwardly sufficiently to let the roll of coins fall out of the carriage.

While I have herein described a preferred embodiment of my invention it is obvious 55 it may be more or less changed in details of construction without in any manner departing from the spirit of the invention.

I claim as my invention:

1. In a coin packaging machine, the combination with a delivery chute, of a gate 60 normally closing the lower end of said chute, a plurality of traveling carriages for receiving singly the rolls of coins from said chute, means connected with each of said 65 carriages for automatically opening said

gate and mechanism for packaging the several rolls of coins while within said carriage.

2. In a coin packaging machine, the combination with a delivery chute, means normally closing the lower end of said chute, a traveling carriage for receiving a single roll of coins from said chute, means connected with said carriage for automatically opening the lower end of said chute in order to permit a roll of coins to fall within said carriage, and mechanism for packaging the roll of coins while within said carriage.

3. In a coin machine, a traveling carriage 80 comprising a trough like main body for receiving the roll of coins, a spring pressed back member within said main body and mechanism secured to said carriage for compressing the ends of said roll of coins. 85

4. In a coin machine, a frame member, a carriage traveling thereon and adapted to receive a roll of coins therein, mechanism upon either end of said carriage for compressing the ends of said roll of coins, and means upon said frame member for automatically operating said compressing mechanism.

5. In a coin machine, a frame member, a traveling carriage thereon adapted to carry 95 a roll of coins, and mechanism for automatically compressing the ends of said roll of coins while within said carriage.

6. In a coin machine, a frame member, a carriage traveling thereon and adapted to 100 carry a roll of coins, spring pressed arms at either end of said carriage adapted to compress said roll of coins at its respective ends and means upon said frame member for automatically actuating said arms during the 105 travel of the carriage.

7. In a coin packaging machine, a mechanism for automatically cutting and gumming a wrapper and delivering the same to the machine comprising a table member over 110 which the wrapper travels, mechanism for delivering said wrapping material to the table, a cutting and a gumming device spring supported above said table, and means for automatically operating said gumming and 115 cutter device.

8. In a coin packaging machine, the combination with an endless traveling conveyer, of a coin receiver carried by said conveyer, means for delivering a roll of coins to said 120 coin receiver, mechanism for wrapping said roll of coins while within said coin receiver and reciprocatory mechanism for sealing each end of said roll of coins while within said coin receiver, said reciprocatory mechanism being automatically operated by said coin receiver.

9. In a coin packaging mechanism, the combination with a traveling belt conveyer, of a coin receiver carried by said conveyer, 125

means for wrapping a roll of coins while within said coin receiver, and a plurality of finger members adapted to be reciprocated across the ends of said wrapped roll 5 of coins to seal the latter and means upon said carriage for automatically operating said finger members.

10. In a coin packaging machine, the combination with a traveling carriage, of a mechanism for delivering a wrapper and a roll of coins to said carriage, means for holding said roll of coins yieldably within said carriage, and mechanism for wrapping and sealing said coins within said wrapper 15 during the traverse of said carriage.

11. In a coin packaging machine, the combination with a traveling carriage, of a mechanism for delivering a wrapper and a roll of coins to said carriage, and means 20 for automatically wrapping, sealing and printing said roll of coins during the traverse of said carriage.

12. In a coin packaging device, the combination with a coin chute, of a spring 25 pressed gate normally confining the coins within said chute, of a traveling carriage adapted to pass beneath the lower end of said chute, and mechanism controlled by said traveling carriage for automatically 30 forcing a roll of coins into said traveling carriage.

13. In a coin packaging device, the combination with a coin chute, of a traveling coin receiver, a spring pressed gate normally 35 confining the rolls of coins within said chute, a bail adapted to extend across the

lowermost roll of coins within the chute and means whereby said bail is automatically operated by the coin receiver to force a roll of coins into said coin receiver. 49

14. In a coin device, the combination with a main frame, of a traveling conveyer mounted on said frame, a plurality of coin receivers rigidly mounted on said conveyer and spaced equal distances apart, a coin 45 chute adapted to deliver a roll of coins to each of said receivers successively, means associated with said conveyer for intermittently ejecting a roll of coins from said chute, and mechanism for actuating said 50 conveyer.

15. In a coin packaging machine, the combination with a main frame, of a traveling belt conveyer mounted upon said main frame, coin receivers carried by said conveyer, means for automatically delivering a wrapper to each of said coin receivers, means controlled by the respective coin receivers for automatically delivering a roll 55 of coins to the latter, frictional mechanism for wrapping the coins while within said coin receivers, reciprocatory mechanism automatically controlled by the coin receivers for sealing the ends of each wrapped roll of coins while within its coin receiver, and 60 means for automatically labeling each wrapped roll of coins. 65
